APPARATUS FOR ADMINISTERING LIQUIDS
 Louis N. Bathish, Glendale, Calif., assignor to Pharmaseal
 Laboratories, Glendale, Calif., a corporation of Calif-
 ornia

Filed Oct. 17, 1960, Ser. No. 62,989
 5 Claims. (Cl. 128—227)

This invention relates to an improved apparatus for administering liquids, and particularly to an inexpensive, disposable apparatus which occupies a minimum of shipping and storage space.

There are many hospital procedures which require the administration of a solution, such as an enema solution, to a patient. This is usually accomplished by attaching a flexible administration tube to the nipple of a porcelain or stainless steel irrigating container, clamping off the tube, preparing the desired solution in the irrigating container, and administering the solution to the patient. The container and its tube must then be thoroughly cleansed and sterilized before the container can be used on another patient. Such cleansing is obviously an unpleasant and time consuming task. Moreover, it is a task which is frequently done during the busiest hours for hospital personnel. Under such conditions, the cleansing operation may not be completely satisfactory, and diseases, such as *Staphylococcus* infections, may be transmitted from one patient to another.

Moreover, the administration tube is difficult to detach, so that it is usually left attached to the container during the cleaning and sterilizing procedures. Under these conditions, the tubes tend to stretch or split and may become detached from the container during an administration, spilling soapy water on the patient and the operator.

The irrigating containers usually used for administering liquids to patients are cylindrical in shape and have a laterally extending nipple to which an administration tube is connected. Thus, these containers cannot be nested one inside another, so that considerable space is required to store or ship the containers.

Collapsible irrigating containers made of thin plastic have been proposed. However, such containers are not self-supporting and a stand or hanger must be available both during mixing of the solution and during the administration procedure. Moreover, these containers have a flimsy, unsubstantial feel which causes concern among hospital personnel that the container will break or slip out of their hands.

It is therefore an object of this invention to provide an inexpensive, disposable apparatus for administering liquids.

Another object of the invention is to provide an apparatus for administering liquids which is self-supporting, but which will occupy a minimum of storage and shipping space.

Another object of the invention is to provide an apparatus for administering liquids in which the administration tube and other components consume a minimum of space, but are adequately protected against damage.

A further object of the invention is to provide an apparatus for administering liquids having a simple, dependable means for attaching the administration tube to the container.

A still further object of the invention is to provide an apparatus for administering fluids having improved hanging means.

Other objects and advantages of the invention will be apparent from the detailed description of the invention and from the accompanying drawings, in which:

FIGURE 1 is an enlarged, elevational view of the invention, with parts cut away to show the internal structure;

2

FIGURE 2 is an exploded, elevational view of the invention;

FIGURE 3 is an elevational view of the invention assembled and ready for use;

FIGURE 4 is a further enlarged, fragmentary, sectional view on the lines 4—4 of FIGURE 3; and

FIGURE 5 is a further enlarged, fragmentary, sectional view on the line 5—5 of FIGURE 3, with portions of the administration tube shown in elevation.

10 As shown in the drawings, containers 10 and 10a have bottoms 11 and 11a and generally cylindrical side walls 12 and 12a. Side wall 12 tapers inwardly toward bottom 11 at an angle of approximately 2 to 5 degrees with the container axis, to facilitate nesting of the containers. 15 Graduations 13a are preferably provided on the inner surface of the container but may also be placed on the outer surface of the container, if desired. The top of the container is open and is provided with an outwardly extending, annular rim 14 from which extends a downwardly depending flange 15. An annular rim 16 projects below bottom 11 to provide a level surface for supporting the container.

Container 10 is preferably made of high density or linear polyethylene, polypropylene, or other, resistant, unbreakable, self-supporting plastic material. The thickness of the material depends on the plastic used, but in the case of polyethylene or polypropylene is preferably about 0.03 to 0.04 inch thick. In any case the side wall 11 should be stiff enough to be self-supporting when the container 10 is full of liquid, and should preferably be translucent or transparent so that the amount of liquid and its flow rate can be observed.

Container 10 is enclosed in a bag 20, made of thin polyethylene or other film type packaging material. Holes 21 are provided in bag 20 to allow air to escape from within the bag when container 10a is nested into container 10. The bottom edge 23 of bag 20 is sealed shut, while the top section 22 is turned down along the inner surface of container wall 12.

40 As mentioned above, the side wall 12 tapers inwardly toward bottom 11 at an angle of about 2 to 5 degrees. The relative dimensions of the container are selected so that the walls 12a of container 10a seat against the walls 12 of container 10 while bottom 11a is still about one-half inch to two and one-half inches above container bottom 11. This provides a compartment 25 in which is located a coiled administration tube 26. A clamp 27, a lubricant packet 28, a hanging bail 29 and a card 30 are also located in compartment 25. Card 30 is preferably circular in shape and serves to protect the contents of compartment 25 after container 10a has been removed. Card 30 may be imprinted with directions for use and preferably has a tab 31 to facilitate its removal from container 10.

45 Administration tube 26 is preferably made of a length of inexpensive, extruded plastic tubing, such as a polyvinyl chloride formulation. One end of tube 26 is provided with a rectal tip 35 having an axial opening and smooth, rounded walls. Rectal tip 35 may be an integral part of tube 26, or it may be detachable so that the container may be reused for an individual patient by merely replacing tip 35. A short distance inwardly from the end, the tip wall is cut away to provide a lateral opening 36. Markings 37 may also be provided at predetermined distances along tip 35 to assist the user in inserting the tip to the desired position.

50 The other end of administration tube 26 is provided with a connector 38, made of a resilient, deformable plastic material, such as a plastisol of polyvinyl chloride, which can be easily cemented to tube 26. Connector 38 has a tapered axial bore into which the end of tube 26 is telescoped. A flange 43 extends into the axial bore at one end of connector 38 and acts as a stop against

which the end of tube 26 rests. Connector 38 has a tapered body 39, the small end of which is adjacent the end of tube 26. The end of connector 38 opposite the end of tube 26 has an annular flange 40. Preferably, tube 26 is cemented only to body 39, not to flange 40, so that pulling on tube 26 will tighten its hold on the wall of container 10. The outer surface of connector 38 is cut away between body 39 and flange 40 to provide an annular groove 41.

Near the bottom of container 10, an offset portion 45 of side wall 12 extends inwardly to a position immediately above the outer edge of bottom 11, thus providing a flat area 46 between offset portion 45 and bottom 11. Flat area 46 may be substantially vertical or it may taper slightly inwardly toward bottom 11 to facilitate molding. The offset portion 45 also serves as a stop to prevent the raw, molded containers from nesting together too tightly.

A circular opening 47 is centrally located in the flat area 46 and is adapted to receive administration tube connector 38. Preferably, the diameter of the wall defining opening 47 is slightly smaller than the diameter of the wall forming the bottom of connector groove 41. Also, the thickness of the wall forming flat area 46 is preferably greater than the distance between the walls defining the sides of groove 41, thus assuring a tight leak-proof fit. For example, I have found that a plastisol connector having a groove 0.016 inch wide and a bottom diameter of 0.48 inch makes a tight, leak-proof fit with a container having an opening 0.46 inch in diameter and surrounded by a wall 0.040 inch thick.

Alternatively, connector 38 may be made of a relatively rigid material, such as rigid polyvinyl chloride, or nylon. In this case, container 10 would be molded of a relatively flexible material, such as low or medium density polyethylene, to allow the wall portion around opening 47 to snap into groove 41. For some uses, the more flexible container would be a disadvantage. On the other hand, the rigid connector could be steam sterilized and the rigidity would make it easier to insert in opening 47.

Bail 29 has a centrally located arch or apex 50. The respective ends of bail 29 are bent at substantially right angles to the plane of bail 29 to form prongs 51, 52, one extending in each direction. As shown in FIGURE 4, container rim 14 has two vertical holes 53, 54 passing therethrough. One end of bail 29 passes through hole 53, so that prong 51 rests against the bottom surface of rim 14, and points toward the rear of container 10. In like manner, the other end of bail 29 extends through hole 54 on the other side of the container, and prong 52 rests against the bottom surface of rim 14, pointing toward the front of container 10. The bail 29 is thus held in an upright position by prongs 51, 52 pushing against the bottom surface of rim 14.

In use, container 10 is removed from container 10a. Card 30 is then removed from container 10 by its tab 31, and the components of compartment 25 taken out. The upper portion 22 of plastic bag 20 is then pulled out and the container 10 removed from the bag. Connector body 39 is then urged into the circular container opening 47, twisting as necessary, until the annular wall section surrounding the opening engages the groove 41. Clamp 27 is then placed on administration tube 26, bent longitudinally around it, then bent transversely to pinch off tube 26. Container 10 is then set on a flat surface and the ingredients of the desired solution are mixed in the container.

Bail 29 is then attached to container 10 by placing it in a position roughly parallel to rim 14 and urging prong 51 through hole 53. Bail 29 is then moved to the upright position and urged as far as possible toward the opposite side of rim 14. In this position, prong 52 is forced through hole 54. The filled container 10 is then suspended above the patient by either placing it on a flat

surface, or by hanging it from bail 29, or it may be held in an elevated position. Lubricant packet 28 is then opened and the tip 35 of the administration tube lubricated and inserted. Clamp 27 is then opened to administer the solution. If additional liquid is desired, clamp 27 can again be shut off and a new batch of solution mixed directly in container 10. When the administration is complete, the entire unit is discarded, and may, if desired, be destroyed by incineration.

In the foregoing description I have described a preferred embodiment in considerable detail for the purpose of illustration. However, it is understood that the structural details may be varied by those skilled in the art, without departing from the spirit of my invention.

I claim:

1. An apparatus for administering liquids comprising: a molded plastic container having an open end, a closed end and a generally cylindrical, tapered side wall; a flat bottom on said closed end, said bottom being adapted to support the container in an upright position on a flat surface; an offset portion of the side wall extending inwardly to a position above the outer edge of the closed end, thus providing a small, substantially vertical, flat side wall portion; an opening passing through and defined by said side wall portion; a connector passing through said opening and having an axial bore parallel to the container bottom, a body and a flange, said body being located on the inside of the container, said flange being located outside of the container and having a larger diameter than said body; and annular, inwardly extending, connector groove between the body and the flange; an annular portion of the flat container wall portion around the opening extending into the connector groove and an administration tube attached to and extending from the connector in a direction parallel to the container bottom.

2. An apparatus for administering liquids comprising: a molded, plastic container having a generally cylindrical, tapered side wall; an open top and a closed bottom end on said container, said top end being of larger diameter than said bottom end; a bag having thin-film side walls, an open end, and a closed end, said closed end lying along the bottom of the molded container and the portion of the bag adjacent the closed end enclosing the molded container; a middle portion of the bag turned down across the top end of the container side wall; and a portion of the bag adjacent the open end thereof lying along the inner surface of the container side wall; and at least one perforation in the wall of the bag between the closed end and the middle portion.

3. An apparatus for administering liquids comprising: a molded plastic container having an open end and a closed end; an outwardly extending rim around said open end; a flat bottom surface on said rim; two holes in opposite sides of said rim, the walls defining said holes being parallel to the container axis; a wire bail, one end of which extends through each of said holes; a prong on each end of the bail, the first of said prongs extending approximately perpendicularly to the plane defined by the wire bail, and the other of said prongs extending approximately perpendicularly to the plane defined by the wire bail, but in the direction opposite to the first prong; and the top surface of said prongs pressing against the bottom surface of the rim, whereby the bail is held in a generally upright position extending axially from the open end of the container.

4. An apparatus for administering liquids comprising: a molded plastic container having a rigid side wall, an open end and a closed end; an opening passing through and defined by said side wall; a flexible, deformable connector passing through said opening and having a flexible body and a flange, said body being located on the inside of the container, said flange being located outside of the container and having a larger diameter than said body; an annular, inwardly extending, connector groove

between the body and the flange; an annular portion of the rigid container wall around the opening extending into the connector groove; a longitudinal passage through the connector body and flange; a flexible administration tube, an end portion of which telescopes into at least a portion of the passage through the connector body and is attached to said body, and a portion of the administration tube adjacent said end portion telescoped through the connector flange, but being free of attachment to said flange, whereby pulling on the administration tube expands the flexible connector body against the inner surface of the rigid container wall.

5. An apparatus for administering liquids comprising: a molded, plastic container having a generally cylindrical, tapered side wall; an open top end and a closed bottom end on said container, said top end being of larger diameter than said bottom end; an outwardly extending rim around said open end; means for attaching a suspension bail to said rim; an offset portion of the side wall extending inwardly to a position spaced from and directly above a portion of the outer edge of the closed bottom end; a small, flat, substantially vertical side wall portion connecting the offset portion to the closed end of the container; an opening passing through and defined by

10

said vertical side wall portion; a bag having a side wall of thin film, an open end, and a closed end, said closed end lying along the bottom of the molded container and the portion of the bag adjacent the closed end enclosing the molded container; a middle portion of the bag turned down across the top end of the container side wall; and a portion of the bag adjacent the open end thereof lying along the inner surface of the container side wall; and at least one perforation in the wall of the bag between the closed end and the middle portion.
